(57) **CLAIM**

The ornamental design for an industrial radio transmitter, as shown and described.

DESCRIPTION

FIG. 1 is a front view of an industrial radio transmitter according to our new design;

FIG. 2 is a rear view of the industrial radio transmitter of FIG. 1;

FIG. 3 is a right side view of the industrial radio transmitter of FIG. 1;

FIG. 4 is a top view of the industrial radio transmitter of FIG. 1;

FIG. 5 is a bottom view of the industrial radio transmitter of FIG. 1; and,

FIG. 6 is a perspective view illustrating the rear and the right side of industrial radio transmitter of FIG. 1.
